UNITED STATES PATENT OFFICE.

ALVIN M. HENDERSON, OF TOLEDO, OHIO.

VEGETATION HOLDER.

Application filed March 2, 1922. Serial No. 540,399.

This invention relates to the care of vegetation.

This invention has utility in connection with the training and care of plants.

5 Referring to the drawings:

Fig. 1 is a view of an embodiment of the invention as adapted to the care and training of carnations;

10 Fig. 2 is a plan view, with parts broken away, showing how the device, in one embodiment thereof, may be used for gating in additional shoots or sprouts;

15 Fig. 3 is a view showing an embodiment of the invention as adapted for the care of more rank growth than carnations, for instance chrysanthemums;

20 Fig. 4 is a perspective view of an embodiment of the invention showing how the supporting of additional stalks may be conveniently done; and

Fig. 5 is a perspective view of a small bow for a single clip such as may be used in handling long single stalks.

25 In loose soil 1 may be inserted riser 2 shown herein as connected by cross bar 3 completing the standard of U-form. Sheet metal clips 4 are designed for conveniently snapping around the standard or risers by spring guide lips 5 passing thereabout. 30 These guide lips 5 are shown as terminating in beads or guides 6 as seats extending parallel to each other and parallel as to the riser 2.

35 In the simple single riser embodiment, or even with the double riser embodiment, the pair of seats 6 may be entered by offsets 7 on a bow 8, which bow 8 is readily placed in position about a single stalk and the offsets 7 are then allowed to slip into 40 seats 6 of the clip 4. This clip 4 is sustained by clip gripping of the riser or standard. The length of the seats 6 in the extent of the clip 4 is such that the offset 7 engaged therewith is in position to 45 sustain this bow or stalk holder against tilting. Accordingly, the clip is fully sustained by mounting on the standard or riser and the bow is fully sustained independent of the standard but directed by the clip.

50 When standards 2, 3, 2, are used, it is convenient to group a large cluster of stalks, say of carnations, by having in parallel and disposed in approximately a horizontal plane, a pair of clips 4 opposing each other. Seats 6 of each one of these clips

may be engaged by an offset 7 of a connecting bow member 9. The holder or training device may be completed by a second such bow member 9 thereby effecting full embracing of a stalk or stalks of the plant.

In practice, many shoots or stalks grow at a different rate than others and sometimes a shoot late to start will grow much more rapidly. In greenhouse production 65 of plants the temperature is usually kept very low, in order to determine just the time of bloom for the flowers. This means that the stalk is quite brittle. Accordingly, in the care of the stalk, it will not stand 70 any bending. With a device as herein shown, any such stray stalk may be conveniently put into the training or embracing holder by gating in, that is, by merely lifting one of the offsets out of the clip 75 and thus opening the gate by swinging the bow 9 out. Then with the other hand the attendant may gradually easily thrust or shove the stray stalk into the embracing region and close the gate.

80 In so far as the stalks, say in their growth, move up together, the clips 4 may be slid up the standard or riser. In those instances where one stalk is very much in advance of the others, or in stalk plants 85 as chrysanthemums, bows 8 may be in position about the stalk and engage the single clip. In instances of a single stalk, instead of having the standard 2, 3, 2, a single standard 10 may be adopted.

89 What is claimed and it is desired to secure by Letters Patent is:

1. A vegetation holder embodying a standard, a spring clip of folded sheet material form having intermediate its extent 95 opposing seats for frictionally engaging the standard to maintain itself in position as to the standard, said clip being provided with terminal beads forming upwardly open seats, and a vegetation guide means having 100 offsets to be slipped down into the clip seats in mounting said means.

2. A vegetation holder embodying an inverted U-shaped standard, clips carried by the legs of the standard, and half ring 105 holders removably mounted in the clips and connecting the clips.

In witness whereof I affix my signature.

ALVIN M. HENDERSON,
